UNITED STATES PATENT OFFICE

132,766

DESIGN FOR A COMBINED DISPLAYING AND DISPENSING CABINET

Louis Richter, Montreal, Quebec, Canada

Application September 2, 1941, Serial No. 103,128

Term of patent 7 years

To all whom it may concern:

Be it known that I, Louis Richter, a subject of the King of Canada, residing in the city of Montreal, Province of Quebec, and Dominion of Canada, have invented a new, original, and ornamental Design for a Combined Displaying and Dispensing Cabinet, of which the following is a specification, reference being had to the accompanying drawings, forming a part thereof.

Fig. 1 is a front perspective view of a combined displaying and dispensing cabinet, showing my new design; and

Fig. 2 is a rear perspective view thereof, some portions being shown in open position.

What I claim is:

The ornamental design for a combined displaying and dispensing cabinet, as shown.

LOUIS RICHTER.
